UNITED STATES PATENT OFFICE.

GRAHAM M. BRUSH, OF GREENWICH, CONNECTICUT.

CARRIER VESSEL.

Application filed January 28, 1925. Serial No. 5,251.

My invention relates to the transportation art, and particularly to the problems surrounding marine shipping, and has for its object the facilitation of the loading and unloading of vessels, convenience in stowage of cargo, and the better preservation of the cargo to be carried, by elimination of the customary rehandling in loading and stowage in the vessels and unloading at the terminal.

Another object is to provide a vessel together with one or more cradles (a term I employ to designate means for supporting a car by its running gear, such, for example, as a movable section of railroad track), to be used in transferring rolling stock, including freight cars, to and from the vessel by means of a crane, hoisting device or the like. These cradles are constructed to mate properly with the permanent construction of the vessel and may be parts of the vessel and may travel at all times therewith.

Another object is to provide such a vessel with a construction adapted to receive and deliver rolling stock from or to a wharf or another vessel, without connecting the rails of the vessel with the rails of the wharf or other vessel. This eliminates a special slip, adjusting pontoons, or other adjusting means now in ordinary use, in loading or discharging rolling stock into or out of a vessel whose relative position varies with that of a fixed wharf at different stages of tide or water level, or for different drafts of the vessel.

Another object is to provide such a vessel with a construction adapted to receive and deliver rolling stock, including freight cars, on or from any one or more of its decks, or in and from the hold, thereby permitting rolling stock to be transported on any one or more of its decks or in its hold.

Another object is to equip the vessel with facilities for receiving or discharging rolling stock at a given point or given points, from or to which the units are moved respectively to or from proper relative position with other units on board, such facilities being so designed as to permit distribution of the weight of the units on board.

Other objects and advantages of my invention will be disclosed in the specification as hereinafter set forth, pointed out in my claims, and illustrated in the accompanying drawings, in which

Fig. 1 is a top plan view illustrating one

form of my invention, showing a fragmentary portion of the carrier vessel;

Fig. 2 is a side view, showing a wharf and a fragmentary portion of said carrier vessel;

Fig. 3 is a cross section, taken on line 3-3 in Fig. 1 in the direction indicated by the arrows; and

Fig. 4 is a fragmentary detail view, in section, of said carrier vessel, showing an opening wherein the cradle rests.

Referring to the accompanying drawings, the reference numeral 10 is used to indicate a carrier vessel, provided with a hold 11. A wharf 12 is provided with tracks 13. Cars 14 are designed to travel on tracks 13, 70 and also on tracks 15, whereon cars 14 are received and moved to desired positions. As shown, a number of parallel tracks 15 are laid in the hold 11 of the vessel 10, and each such track 15 is provided with an opening 75 16 to receive a removable section (which I designate a cradle) 17, which is used in the transfer of cars 14 between the wharf 12 and the hold 11. The tracks 13 on the wharf 12 are also provided with openings 19 to receive the cradle 17, the construction of tracks 13 and 15 being such that when either thereof is resting in mated position with the cradle 17, such track and the track 18 on the cradle 17 forms a continuous trackway. 85 Any desired means may be employed for anchoring the cradle 17 in mated position with either of said tracks 13 and 15.

As shown, a crane 20 is mounted on the vessel 10, and provides the means for lifting, racking and lowering the cradle 17, in conveying cars 14 into, or out of, the vessel 10. The vessel 10 is provided with opening 21 through which the cradle 17 may pass into the hold 11, and guides 22 to positively direct the movement of the cradle 17 are preferably used. The crane 20, or other desired hoisting device, may be located on the wharf 12 or on another vessel, and will function in like manner.

The operation of my device as illustrated is as follows:

A car 14 is moved over track 13 on to tracks 18 on cradle 17, said tracks 13 and 18 being in mated position. The crane 20 then lifts the cradle 17 clear of the side of the hull of the vessel 10, racks it towards and through the opening 21 in the vessel 10 and lowers it into the hold 11, the cradle 17 fitting properly into its opening 16, and the 110

cradle tracks 18 registering with the tracks 15, thereby forming a section thereof. This permits of car 14 being moved over the connecting rails forward or aft as desired. The cradle 17 is then returned to track 13 to take another car aboard, and the operation is repeated until the track 15 is fully loaded. The cradle 17 being adapted to form a part of the vessel 10, cars may be transported on cradle 17 as well as on permanent tracks 15.

In the form of my invention illustrated, each of tracks 15 in vessel 10 is provided with its individual cradle 17. The crane 20 then removes the cradle 17 from a second track 15 and places it in the open section 19 of the wharf track 13, and the operations hereinbefore described are repeated until cars to the desired number have been placed upon the second track 15 and upon all other such tracks.

Obviously, the discharging operation is accomplished in reverse manner.

A single cradle 17 may be used for transporting cars to and from a plurality of the tracks in the vessel if desired, but I prefer to have a cradle for each of the separate tracks on each level in the vessel as means is thereby provided for loading the vessel with its full capacity of cars, for the openings 16 as well as all the tracks 15 are thereby available for car storage while the vessel is in transit.

As shown, to facilitate quick handling of cars 14 the guides 22 are used, each track being provided with its individual registering guides. As there are various designs of guides which may be used with success I have not illustrated or described any particular construction, as the purpose of the guides is to correct any error of judgment of the crane-operator in positioning the cradle 17 in its proper place, and to control any pendulum motion of the hanging cradle 17 while it is being raised or lowered. Although guides are desirable, they are not essential to the successful operation of my device.

Suitable locking devices (not shown) may be provided to secure the rolling stock on the cradle 17 while loading or discharging, or while being transported in the vessel 10, and also to secure the rolling stock on the tracks 15 in the vessel 10 during transportation.

The cradle 17 may be so designed as to rest upon or to fit over the tracks of a wharf or other vessel which are not equipped with an open section to receive the cradle 17, and wedge-shaped connectors (not shown) may be employed to connect the rails 18 of the cradle 17 with the rails on such wharf or other vessel, over which the rolling stock may be moved on to or off of the cradle 17. Similarly, the cradle 17 may be made to connect with the tracks on any one or more

levels of the vessel 10 by means of such connections where desired.

While it is of the essence of my invention that the cradle be bodily movable out of the vessel so as to be clear thereof when supporting the car in registry with the wharf tracks or tracks on another vessel, it is obvious that the transverse movement of the cradle to clear the carrier vessel may be either lateral, as illustrated in the accompanying drawings, or longitudinal, as to a wharf or slip at the bow or stern of the carrier vessel.

The foregoing description is intended as an illustration of my invention, not as a limitation thereof since it is apparent that many changes and modifications may be made without departing from the spirit of my invention as defined in the appended claims.

Having thus described one form of my invention, what I claim and desire to secure by Letters Patent of the United States is:

1. A carrier vessel, rails laid to form a track therein, a cradle for supporting a car by its running gear to register with said track, an opening in the vessel through which the said cradle may be moved and means to move said cradle bodily into and out of the vessel.

2. The combination with a carrier vessel having a track laid therein, of a movable track section adapted to mate with such track and to transport a car thereon, tracks outside of said vessel, and means for bodily moving said track section clear of the vessel for mating said track section at will with said outside tracks or with the track in such vessel.

3. The combination of a carrier vessel, rails laid thereon to form tracks on a plurality of levels, a movable track section, an opening in said vessel for the transfer of said track section in and out of the vessel, and means for bodily moving said track section vertically and transversely of the vessel and adapted to bring said track section at will into registry with one or other of said tracks.

4. The combination of a carrier vessel, rails laid thereon to form tracks on a plurality of levels, a movable cradle adapted to support a car by its running gear so as to register with one or other of said tracks, and means to move said cradle bodily clear of said tracks and transversely of the vessel.

5. The combination, with a carrier vessel having a hold with tracks laid therein, of a removable section in said tracks, there being openings in said vessel through which the removable section may pass, and means to elevate and lower said removable section.

6. The combination, with a carrier vessel having a hold with tracks laid therein,

of a removable section in said tracks, with means to elevate and lower said removable section and position it so that the rails thereon will register with rails on wharf 5 tracks.

7. A device for handling cargo, comprising the combination, with a wharf having railroad tracks thereon, of a vessel, a plurality of tracks on said vessel each having a 10 removable section, means to remove a section and place it in register with the track on the wharf so that rolling stock can be moved on to said section, and to return said section to its original position whereby said 15 rolling stock may be moved on to the tracks on the vessel.

8. A device for handling cargo, comprising the combination, with a wharf having railroad tracks thereon, there being an opening in each of said tracks, of a vessel, a plurality of tracks on said vessel, each track having a removable section corresponding to said opening, means to remove a section and place it in the opening in the track on

the wharf so that rolling stock can be moved 25 on to said section, and to return said section to its original position whereby said rolling stock may be moved on to the tracks on the vessel.

9. A device for handling cargo, comprising the combination, with a vessel, of a railroad track having a section bodily movable into said vessel, the said section having rails thereon which mate longitudinally with tracks on the vessel when said section is 35 placed in the same horizontal plane.

10. A device for handling cargo, comprising the combination, with a wharf having railroad tracks thereon, of a vessel, a plurality of tracks on said vessel, a cradle having rails thereon which mate longitudinally with the tracks on the vessel or the wharf when said cradle is placed in the same horizontal plane, and means to move said cradle into juxtaposition with either the wharf 40 45 tracks or the tracks on the vessel, as desired.

GRAHAM M. BRUSH.
